UNITED STATES PATENT OFFICE.

FRANK W. COLLINS, OF MANISTEE, MICHIGAN.

AIR AND LIQUID SUPPLYING DEVICE.

1,272,379.

Specification of Letters Patent. Patented July 16, 1918.

Application filed January 9, 1917. Serial No. 141,479.

To all whom it may concern:

Be it known that I, FRANK W. COLLINS, a citizen of the United States, residing at Manistee, in the county of Manistee and State of Michigan, have invented a new and useful Air and Liquid Supplying Device, of which the following is a specification.

The present invention appertains to a device for supplying air and liquids to internal combustion engines, and aims to provide a novel and improved device of that character, the introduction of the mixture of air and suitable liquid in the cylinders of the engine having the advantages of removing 15 and eliminating carbon in the cylinders and on the valves, and increasing the mileage per unit of fuel for increasing the efficiency.

The invention has for its object the provision of a pipe having means for holding 20 a suitable liquid or liquids, means for the admission of air, means for controlling the flow of air, and means for controlling the flow of liquid whereby the desired results can be obtained.

It is also the object of the invention to provide an appliance of the nature indicated which is comparatively simple and inexpensive in construction as well as being serviceable and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a vertical median section of the device, portions being shown in elevation.

Fig. 2 is an enlarged sectional detail taken on the line 2—2 of Fig. 1.

The receptacle or reservoir for the liquid is designated generally by the numeral 1, and has transparent side walls, said receptacle being composed of an upright cylindrical glass body 2 and bottom and top plates 3 and 4 between which the body 1 is clamped. The receptacle is covered, and excludes free ingress and egress of air above 55 the liquid level. The bottom plate 3 has a central upstanding tubular member 5 hav-

ing its upper end threaded within a depending central boss 6 with which the top plate 4 is provided, whereby to draw the bottom and top plates toward one another to clamp the 60 body 2. The top plate 4 has a filling opening 8 normally closed by a removable plug or cap 7, which when removed enables the liquid to be poured into the receptacle.

A vertical tubular valve 9 is mounted for 65 rotation within the tubular member 5 and extends through the boss 6 and top plate 4 which are provided with an aperture or bore for accommodating said valve, the lower end of the valve seating upon the bottom plate 70 3. The valve 9 has an upwardly facing shoulder 10 seating against a downwardly facing shoulder 11 with which the top plate 4 is provided, whereby to prevent the upward movement of the valve, and the valve 75 9 has a tubular stem or reduced portion 12 protruding from an upstanding boss 14 with which the top plate 4 is provided. A suitable handle or finger piece 13 is secured upon the stem 12 for turning the valve, and a 80 gland 15 is threaded upon the boss 14 around the stem 12 to prevent leakage. The tubular member 5 and boss 6 are provided with apertures 16 adjacent to and midway between the top and bottom plates, and the 85 valve 9 has complementary lateral apertures 17 to move into and out of registration with the apertures 16, whereby to establish and cut off the communication between the interior of the receptacle and bore of the valve 9. 90

The bottom plate 3 is provided with an upstanding tubular member 18 within the member 5 and of much shorter length, and said member 18 is provided in one side wall with an aperture 19. The bottom plate 3 95 has a vertical bore or duct 20 extending from the lower end of the chamber of the member 18 through a depending boss 21 with which the bottom plate 3 is provided and to the tip of a depending nipple 22 with 100 which the boss 21 is provided. A vertical needle valve 23 extending through the valve 9 axially thereof is threaded, as at 24, adjacent to its tip within the end of the member 18 for adjusting the needle valve, and the bottom plate 3 has a seat 25 at the junction of the member 18 and bore 20 with which the lower end or tip of the needle valve 23 is co-operable, for regulating the flow of air and liquid from the aperture 19 110 into the bore 20. The stem 12 has a reduced portion 26 through which the stem of the

needle valve 23 projects upwardly snugly, the upper end of the needle valve having a hand wheel or disk 27 for screwing the needle valve upwardly and downwardly. A gland 28 is threaded upon the upper end of the stem 12 around the needle valve stem to prevent leakage, and a curved leaf spring 29 has its basal end fitted upon the boss 14 and clamped against the top plate 3 by means of a nut 30 threaded upon the boss. The free end of the spring 29 is engageable with the hand wheel 27 to hold the needle valve in any adjustment.

A depending air inlet tube 31 has its upper end attached to the top plate 4, and its lower end terminates within the receptacle near the bottom plate whereby to admit the air at the lower end of the receptacle, and requiring the flow of the air through the liquid to reach the air space at the upper end of the receptacle. A suitable valve 32 is attached to the plate 4 in communication with the upper end of the tube 31, in order that the flow of air into the receptacle can be regulated or stopped.

A sight feed cup 33 has its upper open end threaded or otherwise engaged upon the boss 21 to inclose the nipple 22, and a cylindrical glass lining or tube 34 is fitted within the cup 33, the side walls of the cup being provided with openings 35 through which the interior of the cup is visible, in order to observe the flow of liquid from the nipple 22, thus providing a sight feed. The bottom of the cup 33 has a nipple or nozzle 36 which is adapted to be screwed into the intake manifold. The nipple 36 has a valve seat 37 and incloses a ball valve 38 which is seatable upwardly against the seat 37 to act as a check valve for preventing the reverse flow of fluid. The valve 38 is prevented from falling from the nipple 36 by means of a diametrical pin 39 provided within said nipple.

In order to admit air and priming fuel into the manifold and cylinders without passing through the liquid in the receptacle, the bottom plate 3 is provided with a radial bore or duct 40 extending from the bore 20 to the margin of the plate 3, and to which the valve casing 41 is attached in communication with the outer end of the bore 40. The valve casing 41 has an upper inlet port 42, and a needle valve 43 is threaded within the casing 41 to regulate the flow of air or liquid from the port 42 into the bore 40. In starting the engine, gasoline or other priming fuel can be poured into the port 42 to flow into the cylinders, and if desired, a priming fuel cup or funnel can be applied to the valve casing 41 to facilitate the pouring of the fuel into the device, the fuel flowing from the valve 41 through the bores or ducts 40 and 20 and through the nipple 36.

In use, the nipple 36 is attached to the in-

take manifold, and a suitable liquid or liquids is poured into the receptacle, for example, kerosene or water, or equal parts of both. The introduction of vapor into the cylinders is beneficial, for the purpose of eliminating carbon and preventing the accumulation thereof, and the introduction of kerosene has recognized beneficial results, to loosen and remove the carbon, especially when assisted by the water vapor.

The needle valve 23 is adjusted to regulate the flow from within the tubular valve through the bore 20, and said valve is held in any adjusted position by means of the spring 29, while the tubular valve 9 can be oscillated manually by means of its handle or finger piece 13. Supposing that the engine is in operation, with the valve 23 opened the desired amount, and the valve 32 opened to admit air, the valve 9 can be oscillated to bring the apertures 16 and 17 into and out of registration, thus intermittently establishing communication between the interior of the valve 9 and the liquid chamber of the receptacle. The valve 9 is only allowed to remain open momentarily, and it can be opened and closed as many times as deemed advisable by the operator, when it is desired to introduce the water vapor and kerosene into the engine at intervals. When the valve 9 is open, the suction created by the engine will extend through the sight feed chamber, bore 20, aperture 19, tubular valve 9, and apertures 17 and 16 into the liquid receptacle, whereby air and liquid will be drawn from the receptacle into the tubular valve and thence to the manifold by way of the aperture 19, bore 20 and sight feed chamber. The air in the upper portion of the receptacle will flow more freely through the uppermost apertures 16 and 17 into the tubular valve 9, whereby air is drawn into the receptacle through the tube 31. The air which enters the receptacle by way of the tube 31 flows upwardly through the liquid and becomes saturated, although a small quantity of liquid flows through the intermediate and lowermost apertures 16 and 17 into the valve 9 to mix with the air which flows downwardly therein at a considerable velocity. Thus, a greater quantity of air is drawn from the receptacle into the valve 9 than the liquid, and this flow of air and liquid is shut off immediately when the valve 9 is closed, said flow being reestablished when the valve is again opened. In this way, the liquid which enters the valve 9 is drawn off through the bore 20, to prevent the accumulation of liquid in said valve, which might occur if the valve 9 were left open too long. The flow of air into the receptacle from the tube 31 serves to agitate the liquid therein and entrain the particles of the liquid. An additional supply of air can be provided

by opening the valve 43, which will not be interfered by the closing of the valve 9. When both water and kerosene are used, the latter will remain on top of the water, 5 so that the water can pass through the lowermost apertures 16 and 17, while the kerosene can flow through the intermediate apertures 16 and 17, it being kept in mind that the air will flow through the uppermost 10 apertures into the valve 9.

Having thus described the invention, what is claimed as new is:

1. A device of the character described embodying a receptacle for both air and liquid 15 having an air inlet, an air and liquid outlet, and means for the flow of air and liquid from the receptacle above and below the liquid level respectively to the outlet, and a manually operable valve for simultaneously 20 establishing and shutting off the flow of air and liquid from the receptacle to the outlet.

2. A device of the character described embodying a liquid receptacle having a tubular member projecting upwardly from its 25 bottom and an outlet in its bottom leading from the lower end of said member, said member being apertured for the flow of liquid and air from the receptacle to the outlet, means within said tubular member 30 for regulating the flow of air and liquid, and air inlet means leading from above to a point below the liquid level.

3. A device of the character described embodying a liquid receptacle having an air inlet and a tubular member projecting upwardly from its bottom and an outlet in its 35 bottom communicating with the lower end of said member, said member being apertured for the flow of air and liquid there- 40 through from the receptacle, a tubular valve rotatable within said member for regulating the flow of air and liquid, and a valve within the tubular valve controlling the flow of air and liquid through the outlet.

45 4. A device of the character described embodying a liquid receptacle having an air inlet and a tubular member extending upwardly from its bottom and an outlet in its bottom communicating with the lower end 50 of said member, said member being apertured for the flow of air and liquid from the receptacle to said outlet, the tubular valve fitting said member and projecting upwardly through the top of the receptacle, said valve 55 controlling the flow of air and liquid, and a

needle valve within said member and valve having its tip lowermost to control the flow of air and liquid through the outlet, said needle valve projecting upwardly beyond the 60 tubular valve.

5. A device of the character described embodying a liquid receptacle having an air inlet and a tubular member projecting upwardly from its bottom and a second tubular member projecting upwardly from its bottom 65 within the first mentioned tubular member, the bottom of the receptacle having an outlet communicating with the lower end of the second mentioned tubular member, said tubular members being apertured for the 70 flow of air and liquid therethrough, a tubular valve rotatable within the first mentioned tubular member for controlling the flow of liquid and projecting through the top of the receptacle, and a needle valve threaded with- 75 in the second mentioned tubular member and having its tip lowermost to control the flow of liquid through said outlet, the needle valve projecting upwardly beyond the upper end of the tubular valve.

80 6. A device of the character described embodying a liquid receptacle having an air inlet and a tubular portion connecting its bottom and top, the bottom of the receptacle having an outlet communicating with the 85 lower end of said portion, said portion having apertures near the bottom and top of the receptacle, and a tubular valve rotatable within said portion for controlling the flow of air and liquid through said apertures. 90

95 7. A device of the character described embodying a liquid receptacle having an air inlet and a tubular portion connecting its bottom and top, the bottom of the receptacle having an outlet communicating with the 95 lower end of said portion, said portion having apertures near the bottom and top of the receptacle, a tubular valve rotatable within said portion for controlling the flow of air and liquid through said apertures, and 100 means for controlling the flow of air and liquid through said outlet.

In testimony that I claim the foregoing as my own, I have hereto affixed my signature in the presence of two witnesses:

FRANK W. COLLINS.
